ABSTRACT

Adamantanes having lower alkyl bridgehead substituents can be used as working fluids in Rankine cycle engines, and particularly in small vapor turbine systems.

POWER GENERATION WITH RANKINE CYCLE
ENGINES USING ALKYLATED ADAMANTANES AS A
WORKING FLUID

BACKGROUND OF THE INVENTION

1. Field of the Invention

This invention relates to Rankine cycle engines, and more particularly to Rankine cycle engines using organic liquids as working substances.

2. The Prior Art

Rankine cycle, high power, multistage, vapor turbines are well known as highly efficient heat engines for the production of power. Such equipment is, in general, highly complex and ill adapted to the production of compact, low weight engines of lesser power. When steam is employed, for example, it is imperative to employ multiple stages to obtain power at usable speeds, and at useful efficiency. Superheat is also essential, if wet steam is to be avoided at the turbine wheel, together with consequent handling and erosion problems.

Small (i.e., less than 1,000 hp.) engines using nozzle turbine wheel systems with associated evaporators and condensers which are suitable for mobile equipment, would preferably utilize a single stage impulse turbine. Preferably, operation should be below the critical temperature of the working fluid to minimize the pressure containment requirements. A boiling point, at atmospheric pressure, of at least 175° C. is also desirable to permit the use of a relatively small air-cooled condenser. Since the efficiency of the engine depends primarily on the temperature of the vapor at the point of expansion relative to the temperature of the condenser, a wide range between the boiling point of the liquid phase and the critical temperature of the working substance is desired. Finally, when used with rotating boilers it is highly desirable that the liquid phase have a relatively high specific gravity in order to minimize the size of boiler required to evaporate the liquid at a given rate. Rotating boilers in which the liquid working substance is contained as a layer on the heated wall of the boiler by centrifugal force are highly efficient evaporators, which provide high quality vapor. High-density liquids are particularly beneficial in such boilers since they minimize the speed of rotation required to maintain the film of liquid in the desired uniform condition. Such engines, evaporators and rotary condensers are described in more detail in the commonly assigned U.S. Pat. applications of William A. Doerner bearing Ser. Nos. 12,296 filed Feb. 18, 1970, now U.S. Pat. No. 3,590,786; 25,857 filed Apr. 6, 1970, and now abandoned; 34,455 filed May 7, 1970, and now abandoned; and 35,712 filed May 8, 1970, now U.S. Pat. No. 3,613,368.

The use of "heavy fluids" as working fluids for turbines has been disclosed by Tabor in U.S. Pat. No. 3,040,528 issued June 26, 1962. In that patent it is pointed out that the efflux velocity of a vapor for expansion in a turbine nozzle between two fixed temperatures is, to a first approximation inversely proportional to the square root of the molecular weight, so that by employing fluids of higher molecular weight, lower efflux velocities and hence lower turbine speeds can be achieved for a given efficiency. This patent further points out that the slope of the saturated vapor line on a temperature-entropy diagram for such liquids is positive rather than negative as in the case of steam so that an expansive superheated vapor rather than a wet vapor is obtained. The excess heat can be transferred by a heat exchanger to the condenser effluent to improve the efficiency of operation. As working fluids, Tabor suggests higher paraffins, chlorobenzene, heavier aromatics and ethers.

SUMMARY OF THE INVENTION

It has now been discovered that adamantanes substituted at one or more of the bridgehead positions with lower alkyl groups, preferably methyl groups possess an outstanding combination of properties which render them suitable as working fluids for Rankine cycle heat engines and particularly for low power turbines.

This invention can therefore be defined as a method of generating power comprising a heat engine in which a working

fluid consisting of at least one compound of the formula

5

- 10 wherein R is alkyl of one to five carbon atoms and R', R'' and R''' are hydrogen or alkyl of one to five carbon atoms with the proviso that the total number of carbon atoms in R, R', R'' and R''' is no greater than eight is converted from liquid to vapor by heat, the vapor does work by expansion, and is thereafter condensed to liquid and recycled.

THE DRAWINGS AND DESCRIPTION OF THE
INVENTION

The generation of power in a small Rankine cycle turbine 20 using 1,3-dimethyladamantane as the working fluid is illustrated by the drawings. In these drawings,

FIG. 1 is a schematic view of a small Rankine cycle turbine system, and

FIG. 2 is a temperature-entropy curve for 1,3-dimethyladamantane.

Turning now to FIG. 1, the working liquid, 1,3-dimethyladamantane is evaporated in the boiler 1. The vapor passes to turbine 2 where it is expanded in the turbine nozzles and employed to run an impulse turbine. On expansion, which is essentially isentropic, the vapor becomes superheated. The exhaust from the turbine is therefore preferably passed through a heat exchanger 3, wherein the excess heat is transferred to the boiler feed. The desuperheated vapor is then passed to the condenser 4 where it is condensed to the liquid phase and the liquid is pumped by pump 5 back to the boiler 1 via the heat exchanger 3.

FIG. 2 shows the temperature-entropy diagram for 1,3-dimethyladamantane. The curve 10-15-14 is the saturated liquid line, the critical temperature 10 being 435° C. and the condenser temperature 14 being 139° C. at a pressure of 2.93 p.s.i.a. The recovering portion of the curve 10-11-13 is the saturated vapor line. Vapor is generated, as shown in the figures at 321° C. along lines 15-11, the boiler pressure being only 112 p.s.i. The vapor is transferred to the turbine and expanded in the nozzle essentially isentropically along lines 11-12, the point 12 being determined by the condenser isobar. The superheated vapor is then cooled and transferred to the liquid state partly by the regenerator and partly by the condenser.

For the above described cycle the Rankine cycle efficiency is 16 percent without regeneration and with 70 percent heat regeneration in the heat exchanger, the Rankine cycle efficiency is 23 percent. The efflux velocity from the nozzle is 55 1,463 ft./sec. permitting operation at a speed of only 40,000 r.p.m. for a 4.5-inch diameter single stage impulse turbine, that is, about one-half of the efflux velocity.

This invention is based on the discovery that the alkyladamantanes have surprisingly high critical temperatures in combination with suitable boiling points for the design of small, air-cooled condensers, in combination with other desirable properties which will be described hereinafter. A comparison of the physical properties of 1,3-dimethyladamantane, $C_{12}H_{20}$, with those of n-dodecane $C_{12}H_{26}$ is given hereinbelow in Table I.

TABLE I

Physical properties of 1,3-dimethyladamantane compared with n-dodecane.

	1,3-dimethyladamantane	n-dodecane
Mol. Wt.	164	170
B.P.°C.	201	214.5
M.P.°C.	-26.5	-12
T _c °C.	435	385
P _{p.s.i.a.}	415	-
d ₄₀	0.90	0.75

It will be noted that in comparison with the straight chain n-dodecane, 1,3-dimethyladamantane exhibits a temperature difference between the critical temperature and the boiling point which is 63.5° C. greater than for n-dodecane. The 1,3-dimethyladamantane also has a substantially higher density permitting the design of more compact rotary boilers in which the liquid is held against the heated surface of the boiler by centrifugal force.

The alkyladamantanes also exhibit exceptional thermal stability in contact with the common metals of engine construction. For example, coupons of aluminum, 304 stainless steel and 1,020 ordinary cold-rolled steel were exposed in evacuated glass tubes to 1,3-dimethyladamantane at 350° C. for 107 days. The aluminum and stainless steel were unchanged while a thin blue coat formed on the 1020 steel. No degradation of the 1,3-dimethyladamantane was observed in these tests.

The alkyladamantanes as a class exhibit low toxicity. For example, exposure of four rats for 4 hours to 947 parts per milion of 1,3-dimethyladamantane resulted in no deaths. The rats exhibited normal weight gain after this exposure.

A further advantage of alkyladamantanes for working fluids is that they have good lubricity and thus permit the use of the working fluid as a bearing lubricant in engines.

Some of the alkyladamantanes, particularly highly symmetrical compounds, have melting points which are above ambient temperatures. For example 1-methyladamantane melts at 103° C. and 1,3,5,7-tetramethyladamantane melts at 67° C. In some applications, such high melting points are not desirable; however, this disadvantage can be overcome by selection of a suitable compound, e.g., 1-ethyladamantane M.P.-60° C. or 1,3-dimethyl-5-ethyladamantane M.P.-80° C. Mixtures of alkyladamantanes, which have lower melting points than the pure compounds, can also be employed.

Alkyladamantanes having from one to four lower alkyl bridgehead substituents are generically useful as working fluids for Rankine cycle engines. In addition to the alkyladamantanes described above, 1-methyladamantane; 1,3,5-trimethyladamantane; 1-n-propyladamantane; 1,3-diisopropyladamantane; 1-n-butyladamantane; 1,3-diethyl-5-methyladamantane; 1-pentyladamantane; 1-ethyl-3,5,7-trimethyladamantane; 1,3-dimethyl-5,7-di-n-propyladamantane; 1-secbutyl-3,5-dimethyladamantane; 1-ethyl-3-propyladamantane and 1-ethyl-3,5-dimethyl-7-propyladamantane.

tane are examples of alkyladamantanes which can be employed alone or in mixtures with other members of the class as working fluids.

Methods of synthesizing alkyladamantanes include those taught by Stetter et al., Chem. Ber. 92 1629 (1959); Koch and Franken, Chem. Ber. 96 213 (1963); Spengler et al., Erdöl und Kohle-Erdgas-Petrochemie 15 702 (1962); Schneider U.S. Pat. No. 3,128,316; Janoski and Moore U.S. Pat. No. 3,275,700 and Schneider U.S. Pat. No. 3,382,288.

10 While the use of bridgehead alkylated adamantanes have been described more particularly with reference to the generation of power with small, portable vapor turbines operating on the Rankine cycle, it will be realized that the use of these compounds is not limited to this particular application. The adamantanes with alkyl substituents at the bridgeheads are also useful with larger turbines, and with reciprocating engines which operate on the Rankine cycle.

15 The foregoing detailed description has been given for clarity of understanding only and no unnecessary limitations are to be understood therefrom. The invention is not limited to the exact details shown and described for obvious modifications will be apparent to those skilled in the art.

The embodiments of the invention in which an exclusive property or privilege is claimed are defined as follows:

20 25 1. In a method of generating power in which a working fluid is converted from liquid to vapor by heat, said vapor is thereafter condensed to a liquid and recycled, the improvement comprising using a working fluid consisting of at least one compound of the formula

30 wherein R is an alkyl group of one to five carbon atoms and R', R'', and R''' are separately hydrogen or an alkyl group of one to five carbon atoms.

40 2. The method of claim 1 in which said power is obtained by expansion of said vapor in a nozzle-turbine wheel system.

3. The method of claim 2 in which the liquid is 1,3-dimethyladamantane.

4. The method of claim 2 in which said liquid is heated in a 45 rotary boiler.

5. The method of claim 4 in which the liquid is 1,3-dimethyladamantane.
